LIFEBOAT LAUNCHING DEVICE

John F. Ryan, Baltimore, Md.

Application October 6, 1936, Serial No. 104,325

1 Claim. (Cl. 9—22)

The invention relates to a life boat launching device and more especially to means for launching ships' boats.

The primary object of the invention is the provision of a device of this character, wherein through the use of caster rollers or wheels clamped in position or place upon a life boat trackage of such rollers or wheels can be had upon the hull of a parent vessel particularly when the same has listed so as to assure safety to the occupants of the life boat when being lowered into the water without liability of the capsizing of such life boat.

Another object of the invention is the provision of a device of this character, wherein the same is conveniently attached to and removed from a life boat when suspended by a davit on board a parent ship so that when the life boat is being lowered without regard to the listing of the parent ship there will be no interference with the said life boat and the same will be maintained on an even keel to avoid the turning over or capsizing of such life boat while being lowered into the water, the device being separable from the life boat with dispatch after it has reached the water and also such device when removed from the boat can be conveniently stored within the parent ship or the boat itself and occupying the least possible space when not in use.

A further object of the invention is the provision of a device of this character, wherein the construction thereof is novel in form and affords a cradle for a life boat to assure safety in the placing of the life boat in the water to eliminate the possibility of capsizing thereof and also is susceptible of attachment to varying sizes of life boats for the cradling thereof.

A still further object of the invention is the provision of a device of this character, which is extremely simple in its construction, thoroughly reliable and effective in its operation, easily attached to and removed from a life boat and attached and detached with dispatch, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is an elevation of a life boat suspended by a davit showing the device constructed in accordance with the invention applied thereto.

Figure 2 is an end elevation thereof.

Figure 3 is a fragmentary side elevation partly in section of a portion of the device.

Figure 4 is an enlarged fragmentary sectional view of certain parts shown in Figure 3.

Figure 5 is a fragmentary top plan view showing a portion of the tie rod and coupling of the device.

Figure 6 is an elevation of the intermediate adjuncts of the device as applied to the boat.

Figure 7 is a side elevation thereof.

Figure 8 is a top plan view.

Similar reference characters indicate corresponding parts throughout the several views in the drawings.

Referring to the drawings in detail, A designates generally a life boat of conventional kind and B its keel ridge, the boat when upon a parent ship is suspended or supported by a davit, a portion thereof being indicated at C, so that such boat may be cast outboard for reaching the water.

The device constituting the present invention comprises a pair of outer and a single intermediate wheel fork 10 and 11, respectively, these having journaled therein wheels or rollers 12. The outer forks 10 are provided with saddles 13 constituting seats for the keel ridge B and such saddles are bolted or otherwise secured to the lower ear ends 14 of lowermost tubular rods 15 of a pair of extensible clamping arms, the uppermost tubular rods of which are indicated at 16, these being joined with the lowermost rods 15 through turn buckles 17. The uppermost rods 16 are slidably telescoped into coupling sleeves 18 which through linkage 19 are hung from hook-like brackets or clamps 20 which engage over the upper edge of the side of the hull or body of the boat A. Each sleeve 18 carries a spring tensioned trigger latch 21 for engaging in a keeper socket 22 provided in each of the uppermost tubes 16 for detachably latching the same in the sleeve. The arms including the tubes 16 are outwardly bowed correspondingly to the bow or bulge of the body or hull of the boat A and in this manner the wheel forks 10 with the wheels 12 are clamped in place on the said boat as is clearly shown in Figures 1, 2 and 3 of the drawings.

The saddles 13 having fixed thereto perforated ears 23 which extend toward each other from the said saddles and in which are separately engaged hook ends 24 of a pair of tie rods 25, these being adjustably joined with each other through the medium of a turn buckle 26, and in this manner the said forks 10 are adjustably spaced from each other in their clamped position upon the boat A.

The intermediate fork 11 carrying the wheel

12 is fixed to the lower end of a swinging lever 27 pivoted at 28 to a sector rack 29 fixed to a clamping bracket or jaw 30 adapted to be fastened by a set screw 31 in place upon the side of the boat 5 A intermediate with relation to the forks 10. The lever 27 at its handle end 32 is fitted with a hand release spring pressed latching bolt or 10 detent 38 selectively engageable with the teeth of a keeper rack 39 formed at the upper portion 15 of the segment 29. The lever 27 below its pivot 28 has connected thereto a coiled retractile spring 40 which is also fastened to the bracket 30 and this spring urges the fork 11 inwardly toward 20 the boat A when the bracket is secured thereto 25 and saddling the upper edge of the side thereof while the detent or bolt 38 latches said lever against inward swinging movement counter to the action of the spring 40 and thus holding the fork 11 with the wheel 12 outwardly spaced from 30 the side of the boat A at the desired distance within the range of the rack 39. These rollers or wheels 12 make contact with the hull of a parent ship carrying the life boat A when such ship has listed so as to enable the boat A when 35 being lowered to maintain an even keel and avoiding any possibility of the capsizing of the boat when being lowered from the said parent ship into the water, the rollers being adapted to travel upon the hull of said parent ship when listing during the lowering of the life boat to the water. The device constituting the present invention is 40 readily and quickly demountable from the boat A so as to permit the storage thereof when not

in use and also when the said boat A has been lowered into the water. The device is carried by the life boat A when the same is lowered by the davit from the parent ship and will assure safety and avoid capsizing of such boat when 5 placing it in the water.

The device is readily adjustable for fitting varying sizes of life boats and is readily and easily attached and detached for use and disuse thereof. 10

Each trigger latch 21 is carried by a clamping collar 41 made secure to and embracing each sleeve. 15

What is claimed is:

A life boat launching apparatus comprising 16 a pair of clamp devices adapted to be removably secured at spaced points along the side of a life boat; each clamp device consisting of a wheel fork having a notched saddle for seating a keel ridge of a boat therein, a wheel mounted in the 20 fork, a hook like member engageable with the upper side of the boat, a rod like member secured to and outwardly bowed from said saddle of said wheel fork for spanning the side of the boat, a sleeve member swiveled to said hook like member 25 and detachably engaged over the free end of the rod like member, a releasable latch securing said rod like member and sleeve member in telescopic relationship and coupling means connecting said wheel forks consisting of a rod secured to each 30 wheel fork and a turn buckle connecting the rods.

JOHN F. RYAN.
